APPARATUS FOR PRESSING SOLES ON
SHOE BOTTOMS

Charles K. Woodman and Napoleon S. Ferland,
Beverly, Mass., assignors to United Shoe Ma-
chinery Corporation, Flemington, N. J., a cor-
poration of New Jersey

Application December 3, 1947, Serial No. 789,380

21 Claims. (Cl. 12—38)

1

This invention relates to apparatus for pressing the soles of shoes, and is herein disclosed as embodied in a pad box useful in such operations as sole-laying, direct pressure leveling, or cement sole-attaching.

In carrying out the aforementioned operations, and more particularly in connection with sole-laying and cement sole-attaching operations, it is desirable that heavy pressure be applied to the marginal area of the shoe bottom and that a lesser pressure be applied to the area of the shoe bottom inwardly of the margin. By thus concentrating the maximum pressure applied to the sole around its margin the capacity of the machine is most effectively utilized, close fitting margins are obtained and small irregularities of the shoe bottom are not transferred through the shoe to the sole to become visible in the finished shoe as might happen were as heavy pressure applied to the midportions of the sole as is required for obtaining optimum results along the margin. It is also desirable that the pad box be capable of operating on a wide range of styles and sizes without the necessity for making manual adjustments and that a substantially uniform pressure be applied throughout the marginal portion of the shoe. It is sometimes desirable, however, that the pressure along the shank portion of the shoe be somewhat greater than that along the forepart.

It is an object of the present invention to provide an improved pad box having the advantages outlined above. To this end and in accordance with a feature of the invention, the pad box includes a suitably formed rubber pad over which is a resilient metal blanket so formed as to apply pressure to the sole of the shoe in a manner to accomplish the above objectives. As illustrated herein, the blanket is composed of a plurality of metal bars extending transversely of the pad and having the capacity for conforming to the lateral curvatures of the shoe bottom as well as to the lengthwise curvatures. The bars are preferably stiff and preformed to approximate the lateral contours of the shoe bottom and are supported in contiguous relation by flexible means permitting the blanket to conform readily to the lengthwise curvatures of the shoe bottom.

To insure the application of substantially uniform pressures to adjacent portions of the shoe bottom and in accordance with a further feature of the invention, the pad which underlies the blanket is of soft rubber or like material and is confined on the top by the metal blanket and on all other sides by a supporting metal box. 55

2

Upon depression of a bar of the blanket in response to pressure applied thereon the rubber beneath the bar will flow, acting upon adjacent bars of the blanket to force them upwardly in such manner that the pressure exerted by the different portions of the blanket lengthwise of the box will be substantially uniform. Pressure is concentrated along the marginal portion of the shoe bottom by this arrangement. Because the bars are capable of bending lengthwise, the bars bend upwardly beyond the area of contact with the shoe bottom. The degree of bending depends upon the ratio of the length of the bar under the shoe and the length of bar beyond the shoe. In the shank area where the length under the shoe is short, relative to the length beyond the shoe, considerable bending will occur, and since the shoe bottom in this area has considerable lateral curvature, the bars will exert maximum pressure near the edge of the shoe. To augment this action of the bars, the pad is recessed along a central portion in its upper face so that the midportions of the bars of the blanket are out of contact therewith. Consequently greater pressure will be exerted by those portions of the bars which are supported directly by the rubber than by those portions which bridge the recess in the rubber pad.

Inasmuch as the blanket is of sufficient size to accommodate a wide range of sizes of shoes, those bars at the toe end of the blanket will not be covered by the work except when the largest size shoe is placed thereon. To prevent excessive upward movement of those bars forwardly of the toe end of the shoe, and in accordance with a further feature of the invention, stiffening bars extending lengthwise of the pad box are associated with this end of the blanket, thereby preventing curling up of the extreme toe end of the sole which might otherwise take place and would mar the appearance of the finished shoe.

The above and other features of the invention, including various novel combinations of parts and details of construction, will now be described by reference to the drawings and pointed out in the claims.

In the drawings,

Fig. 1 is a front elevation of a portion of one form of machine embodying the invention;

Fig. 2 is a plan view of one form of pad blanket, embodying the invention, parts thereof being broken away to disclose other parts located therebelow;

Fig. 3 is a side elevation of a pad with which the blanket is adapted for use;

Fig. 4 is a section through the pad and blanket along the line IV—IV of Fig. 2;

Fig. 5 is a section through the complete pad box, this section being taken along the line V—V of Fig. 2, and

Fig. 6 is a section through the pad box along line VI—VI of Fig. 2.

The invention is illustrated as embodied in a pad box 10 having trunnions 12 (only one of which is shown) by which the pad box is supported for rocking movement in a yoke 14 of a sole laying machine which may be of the type illustrated and described in application for Letters Patent of the United States No. 2,459,845, dated Jan. 25, 1949, in the names of Thomas H. Seely and Lambert S. Linderoth Jr. Such a machine includes an arm 16 supporting a cross-head 18 by which are carried a heel post 20 and a toe post 22. Carried by the heel post 20 is a heel support 24 in the form of a last engaging plate, and a toe support in the form of a roll 26 is carried at the lower end of the toe post 22. After a shoe S with an outsole O to be laid thereon has been placed on the pad box 10, the yoke 14 is moved upwardly to carry the shoe into engagement with the heel and toe supports thereby to apply pressure to the shoe bottom as illustrated in the aforementioned application. The pad box 10 will rock if necessary about the axis of the trunnions 12 so that the pressure on the heel and toe portions of the shoe will be equalized. To eliminate unnecessary rocking movements of the pad box and to hold it, after the relief of pressure, in the position into which it has moved relatively to the yoke 14 when pressure is applied to the shoe bottom, a detent 28 may be carried by the pad box for engagement with an adjacent surface of the yoke 14 to act as a brake against rocking movement.

The pad box 10 includes a box or container 30 in which is mounted a soft, resilient pad 32 (Figs. 3, 4, 5 and 6) of material such as soft rubber which will yield readily upon the application of pressure thereto. Whereas a solid block of rubber is illustrated herein it will be understood that the pad may take other forms. For example, a fluid filled bag of rubber or like material, or a bag full of sand or the like may be employed. The upper face of the pad 32 is preferably provided with a recess 34 which, as shown in Fig. 5, is relatively deep in that portion which is to underlie the shank portion of the shoe and is relatively shallow in that portion (Fig. 6) that is to underlie the forepart of the shoe although the particular shape is not critical and may be modified. The recess is wider in the forepart portion than in the shank portion and is shaped in plan as illustrated in Fig. 2, the width of it being such that it will lie wholly within the marginal portions of the smallest shoe which is to be operated upon. The purpose of this recess will appear as the description proceeds. The bottom of the pad 32 may be flat but it is illustrated herein as being provided in its bottom face with a recess 36 which underlies that portion of the pad on which the shank portion of the shoe will rest in the sole laying operation. Fitted into the recess 36 is a metal block 38 which provides increased rigidity for that portion of the pad 32 above the block 38 thereby to provide for the application of maximum pressure to the shank portion of the shoe.

Located in contact with the top face of the pad 32 is a metal blanket 40 which is formed of a plurality of transversely extending stiff

metal rods or bars 42 which may be formed of steel. The ends of these bars are formed with loops as shown in Figs. 2, 5 and 6 and through these loops pass flexible cables 44 which hold the bars 42 of the blanket in assembled relation. Each of the cables 44 has secured to one end thereof a collar 46 forming an abutment for the adjacent bar 42. Slidable on the other end of each cable is a collar 48 which abuts the adjacent bar 42 and is urged toward the collars 46 by springs 50 surrounding the cables and acting against fixed collars 52 secured to the cables. It will be seen that there is thus formed a blanket which is flexible lengthwise of the pad box, the bars of the pad being held together by the springs 50 to form a substantially continuous surface. The bars are curved transversely of the blanket in accordance with the transverse curvatures of a shoe bottom and the upper face of the pad 32 is similarly contoured so that the bars 42 are in close contact with the pad 32 except for that portion of the pad which is recessed at 34.

Between those bars 42 at the toe end of the blanket 40 and the adjacent surface of the pad 32 is a set of longitudinally extending stiff bars 54, the forward ends of which are looped over a cable 56 and the rear ends of which are bent and received in a transversely extending recess 58 in the pad 32. These bars 54 extend rearwardly a sufficient distance to underlie the toe of the smallest shoe which will be operated upon. These bars stiffen the toe end of the blanket 40 so that it cannot bend lengthwise of the pad as readily as that portion which is located rearwardly of the bars 54. It will be noted that the bars 42 do not extend to the extreme heel end of the pad 32 but terminate somewhat short of it and between the rearmost bar 42 and the end of the pad 32 is a metal plate 60 which extends forwardly a sufficient distance to underlie the heel end of the smallest shoe to be operated upon.

As shown in Figs. 3, 5 and 6, the pad 32 is cut away at 62 along both sides thereof to accommodate the cables 44 so that the blanket 42 provides a relatively continuous smooth surface. The bars are illustrated as being circular in cross section and of small diameter but the cross sectional shape of the bars may be varied as desired. To provide a sufficiently smooth sole engaging surface a flexible cover 64 is placed on top of the blanket 40. This cover may be of leather, rubber or any material suitable for the particular operation and type of work to be done. Secured to the sides of the box 10 and extending inwardly over the marginal portions of the blanket 40 and the cover 64 are plates 66 which maintain the blanket and the pad in assembled relationship within the box.

It will be noted that the pad 32 is confined on its bottom and four sides by the box 30 and at the top by the flexible metal blanket 42. When a block of rubber or similar material is thus confined, and pressure is applied to one portion of it to distort it inwardly, the pressure is transmitted to the immediately adjacent portions of the pad in a manner analogous to the transmission of hydraulic pressure. Because of this characteristic of rubber, when a shoe is placed on the pad box and pressure is applied thereto, unless the blanket is shaped exactly like that of the shoe bottom, some of the bars 42 of the blanket will be depressed before others exert any pressure on the 75 shoe bottom. The depression of some of the bars

causes the rubber to flow whereupon other bars of the blanket will be forced upwardly thereby equalizing to a large extent the final pressure which is exerted throughout the shoe bottom. In the absence of the longitudinally extending bars 54 those bars 42 which are located forwardly of the toe end of a shoe would be forced upwardly a considerable distance when pressure is applied to the shoe and would tend to roll up the toe end of the outsole. Since the forepart of a shoe bottom is relatively flat, extreme flexibility in this region is not necessary. Thus the increased rigidity in this area has no detrimental effect. It will be understood, however, that the blanket is capable of flexing at the toe end upon the application of heavy pressure so that an adequate bond is effected between the sole and the shoe at this portion thereof.

The bars 42 are stiff, but are capable of bending under heavy pressure to accommodate the lateral curvatures of the shoe bottom. By pre-forming the bars 42 laterally of the pad box to approximate the lateral curvatures of a shoe bottom it will be understood that only slight lateral bending of the bars takes place during the sole pressing operation to cause the blanket to conform to the lateral curvatures of the particular shoe which is placed thereon. By recessing the top of the pad 32 as at 34, the action of the bars in concentrating the maximum pressure to the marginal portions of the shoe is augmented. Furthermore, by shaping the pad as indicated in Fig. 5 beneath the shank portion there is a tendency for the pad to bulge up along the marginal portions of the outsole in response to the application of pressure through the blanket 40 so that close fitting margins are produced.

From the above it will be seen that we have produced a pad box which may be employed for various sole pressing operations such as laying, leveling or attaching, in which the distribution of pressure along adjacent parts of the margin is substantially uniform but along the shank portion it may be somewhat greater than along the forepart, and that lesser pressure is applied to that portion of the sole inwardly of the margin. The pad box is capable of accommodating shoes of various sizes and styles without the necessity of making any manual adjustments. The effectiveness of the blanket with respect to the action of the bars on different portions of the shoe bottom may be readily changed by using a pad of the proper shape in so far as recess 34 in the top face is concerned and the recess 36 with the metal insert 38 in the lower face is concerned.

Having thus described the invention what we claim as new and desire to secure by Letters Patent of the United States is:

1. Apparatus for pressing soles on the bottoms of shoes, comprising a soft resilient pad, and a metal blanket entirely covering said pad, said blanket comprising a plurality of stiff metal bars arranged in side-by-side relation to form a substantially continuous surface, said bars being connected together for bodily movement relatively to one another and also being each yieldable in response to pressure of a shoe thereon to conform to the lateral and heightwise curvatures of the bottom of the shoe.

2. Apparatus for pressing soles on shoe bottoms comprising a soft resilient pad and a metal blanket entirely covering said pad, said blanket comprising a plurality of transversely extending stiff metal bars capable of conforming to the lateral curvatures of a shoe bottom in response to

the application of pressure to a shoe placed thereon, and means for supporting said bars in contiguous relation to form a substantially continuous surface conformable to the lengthwise curvatures of the shoe bottom.

5 3. Apparatus for pressing soles on shoe bottoms comprising a soft resilient pad and a metal blanket on said pad, said blanket comprising a plurality of transversely extending stiff metal bars shaped to conform substantially to the lateral curvatures of the forepart and shank portions of the bottom of a shoe, and means for supporting said bars in contiguous relation to form a substantially continuous surface conformable to the lengthwise curvatures of the shoe bottom.

10 4. Apparatus for pressing soles on shoe bottoms comprising a soft resilient pad and a metal blanket on said pad, said blanket comprising a plurality of transversely extending stiff metal bars shaped to conform substantially to the lateral curvatures of the forepart and shank portions of the bottom of a shoe, means for supporting said bars in contiguous relation to form a substantially continuous surface conformable to the 15 lengthwise curvatures of the shoe bottom, and means rendering one end of said blanket resistant to lengthwise bending.

20 5. A flexible blanket for a sole-pressing pad comprising a plurality of transversely extending stiff metal bars individually shaped to provide a substantially continuous surface conforming substantially to the lateral curvatures of the forepart and shank portions of a shoe bottom, and flexible supporting means for the ends of said 25 bars providing lengthwise flexibility of the blanket.

30 6. A metallic blanket for a sole-pressing pad having a surface preshaped substantially in accordance with the lateral curvatures of the forepart and shank portions of a shoe bottom, said 35 blanket having a slight lateral flexibility and great lengthwise flexibility.

40 7. A metallic blanket for a sole-pressing pad having a surface preshaped substantially in accordance with the lateral curvatures of the forepart and shank portions of a shoe bottom, said blanket having a slight lateral flexibility and great lengthwise flexibility throughout a substantial portion of its length but being substantially 45 rigid lengthwise of the blanket at one end thereof.

50 8. A flexible blanket for a sole-pressing pad comprising a plurality of transversely extending stiff metal bars of circular cross section individually shaped to provide a substantially continuous surface conforming substantially to the lateral curvatures of the forepart and shank portions of a shoe bottom, each of said bars being 55 formed with loops at its ends and flexible cables passing through said loops and providing lengthwise flexibility of the blanket.

60 9. Apparatus for pressing soles on the bottoms of shoes having a metal blanket arranged to engage the bottom face of the shoe, said blanket comprising a plurality of stiff metal bars arranged in side-by-side relation to form a substantially continuous surface, each of said bars extending across the entire width of the blanket, 65 the bars being each yieldable and also bodily movable relatively to one another to conform to the lateral and heightwise curvatures of the sole in response to pressure of the shoe against them, and yielding means backing up said bars and 70 arranged to increase the pressure of said bars 75

against the bottom of the shoe along selected portions of the shoe bottom.

10. Apparatus for pressing soles on the bottoms of shoes having a metal blanket arranged to engage the bottom face of the forepart and shank portion of a shoe, said blanket comprising a plurality of stiff metal bars arranged in side-by-side relation to form a substantially continuous surface, the bars being each yieldable and also bodily movable relatively to one another to conform to the lateral and heightwise curvatures of the sole in response to pressure of the shoe against them, a soft resilient pad underlying said bars, and a rigid box engaging the edge and bottom faces of said pad to confine it while permitting it to yield to conform to the contour of the shoe bottom with said bars thereby substantially to equalize the pressure of said bars along adjacent portions of the shoe bottom.

11. Apparatus for pressing soles on shoe bottoms comprising a pad box, a soft resilient pad in said box having its bottom and all sides thereof confined by the box, and a metal blanket in contact with the top face of the pad, said blanket being flexible lengthwise of the pad and relatively stiff transversely of the pad.

12. Apparatus for pressing soles on shoe bottoms comprising a pad box, a soft resilient pad in said box having its bottom and all sides thereof confined by the box, and a flexible metal blanket in contact with the top face of the pad, said blanket comprising a plurality of stiff metal bars extending transversely of said pad and providing a longitudinally flexible supporting surface.

13. Apparatus for pressing soles on shoe bottoms comprising a pad box, a rubber pad in said box having its bottom and all sides thereof confined by the box, and a flexible metal blanket in contact with the top face of the pad, said blanket comprising a plurality of stiff metal bars extending normal to the longitudinal axis of said pad throughout a substantial length of the pad box and providing a longitudinally flexible supporting surface for the forepart and shank portion of a shoe, and other bars underlying said first named bars along a selected portion of the length of the blanket and extending normal to the first named bars for reinforcing the first named bars.

14. Apparatus for pressing soles on shoe bottoms comprising a pad box, a rubber pad in said box having its bottom and all sides thereof confined by the box, and a flexible metal blanket in contact with the top face of the pad, said blanket comprising a plurality of stiff metal bars extending transversely of said pad throughout a substantial length of the pad box and providing a longitudinally flexible supporting surface, and a plurality of stiff metal bars extending lengthwise of the pad box for a portion of its length from one end thereof and providing a relatively rigid supporting surface at said end of the box.

15. Apparatus for pressing soles on shoe bottoms comprising a pad box, a rubber pad in said box having its bottom and all sides thereof confined by the box, and a flexible metal blanket in contact with the top face of the pad, said blanket comprising a plurality of transversely extending stiff metal bars shaped to conform to the lateral curvatures of the forepart and shank portions of the sole of a shoe and connected to form a substantially continuous surface conformable to the lengthwise curvatures of the shoe bottom.

16. Apparatus for pressing soles on shoe bottoms comprising a pad box, a rubber pad in said box having its bottom and all sides thereof confined by the box, and a flexible metal blanket in contact with the top face of the pad, said blanket comprising a plurality of transversely extending stiff metal bars shaped to conform to the lateral curvatures of the forepart and shank portions of the sole of a shoe and connected to form a substantially continuous surface conformable to the lengthwise curvatures of the shoe bottom, and means for rendering a selected portion of said blanket resistant to lengthwise bending.

17. Apparatus for pressing soles on shoe bottoms comprising a pad box, a rubber pad in said box having its bottom and all sides thereof confined by the box, and a flexible metal blanket in contact with the top face of the pad, said blanket comprising a plurality of transversely extending stiff metal bars shaped to conform to the lateral curvatures of the forepart and shank portions of the sole of a shoe and connected to form a substantially continuous surface conformable to the lengthwise curvatures of the shoe bottom, and means rendering one end of said blanket resistant to lengthwise bending.

18. Apparatus for pressing soles on shoe bottoms comprising a pad box, a rubber pad in said box and having its bottom and all sides thereof confined by the box, and a flexible metal blanket in contact with the top face of the pad, said pad having a depression in its central portion bridged by said blanket.

19. Apparatus for pressing soles on shoe bottoms comprising a pad box, a rubber pad in said box and having its bottom and all sides thereof confined by the box, and a flexible metal blanket in contact with the top face of the pad, said blanket comprising a plurality of transversely extending stiff metal bars shaped to conform to the lateral curvatures of the forepart and shank portions of the sole of a shoe and connected to form a substantially continuous surface conformable to the lengthwise curvatures of the shoe bottom, the top surface of said pad having a contour similar to that of the blanket but having a depression in its central portion bridged by said bars.

20. Apparatus for pressing soles on shoe bottoms comprising a pad box, a rubber pad in said box and having its bottom and all sides thereof confined by the box, and a flexible metal blanket in contact with the top face of the pad, said blanket comprising a plurality of transversely extending stiff metal bars shaped to conform to the lateral curvatures of the forepart and shank portions of the sole of a shoe and connected to form a substantially continuous surface conformable to the lengthwise curvatures of the shoe bottom, the top surface of said pad having a contour similar to that of the blanket but having a depression in that portion which underlies the shank and forepart of a shoe on the blanket, said depression being narrow at one end and wider at the other end and being bridged by the bars.

21. Apparatus for pressing soles on shoe bottoms comprising a pad box, a rubber pad in said box and having its bottom and all sides thereof confined by the box, and a flexible metal blanket in contact with the top face of the pad, said blanket comprising a plurality of transversely extending stiff metal bars shaped to conform to the lateral curvatures of the forepart and shank portions of the sole of a shoe

and connected to form a substantially continuous surface conformable to the lengthwise curvatures of the shoe bottom, the top surface of said pad having a contour similar to that of the blanket but having a depression in that portion which underlies the shank and forepart of a shoe on the blanket, said depression being narrow and deep at that portion which underlies the shank and wider and shallow in that portion which underlies the forepart of a shoe on the blanket, said depression being bridged by said bars.
